US0D1047964S

(12) **United States Design Patent** (10) **Patent No.:** **US D1,047,964 S**
(45) **Date of Patent:** **** Oct. 22, 2024**

(54) **HEADPHONES**

(71) Applicant: **Charles Colbert**, Stonecrest, GA (US)

(72) Inventor: **Charles Colbert**, Stonecrest, GA (US)

(**) Term: **15 Years**

(21) Appl. No.: **29/897,905**

(22) Filed: **Jul. 20, 2023**

Related U.S. Application Data

(60) Continuation of application No. 29/893,903, filed on Jun. 4, 2023, now Pat. No. Des. 1,000,415, which is a division of application No. 29/861,073, filed on Nov. 25, 2022, now Pat. No. Des. 988,290.

(57) **CLAIM**

The ornamental design for headphones as shown and described.

DESCRIPTION

FIG. 1 is a front perspective view of headphones showing the new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof; and,

FIG. 8 is another front perspective view thereof.

The evenly spaced, dot dot broken lines depict portions of the headphone in which the design resides; the dot dash broken lines adjacent the shaded areas represent the bounds of the claimed design. All broken lines form no part of the claimed design.

1 Claim, 6 Drawing Sheets
